UNITED STATES PATENT OFFICE.

EDMUND SCHRÖDER, OF BERLIN, GERMANY.

REGULATING GEAR.

Application filed August 24, 1921. Serial No. 495,146.

To all whom it may concern:

Be it known that I, EDMUND SCHRÖDER, a citizen of the German Republic, and residing at Nos. 48-51 Maybach-Ufer, Berlin, 5 Germany, have invented certain new and useful Improvements in Regulating Gears, of which the following is a specification.

This invention relates to a planet-wheel change-speed gear and is so constructed as 10 to permit of being employed as a change-speed gear, its particular effect being that variations in the number of revolutions of a driving shaft are transmitted to a driven shaft coupled with the gear only in a reduced measure. This is important for purposes where the number of revolutions of a shaft shall be as uniform as possible and where perfect uniformity of the driving motor cannot be attained with complete 15 pendableness.

My invention is illustrated by way of example in the accompanying drawing in which Figure 1 is an axial section through a gear constructed according to this invention, and Figure 2 is a plan of the same.

b is a member of the planet-wheel gear; it is its driving wheel which is secured to the driving shaft *b'*. *c* and *d* are the planet wheels of this gear. The planet-wheels are 30 bevel-wheels in the instance shown attached to a carrier *m*, and encompassed by a band *m'* to which is affixed an angular arm *d'* forming at its end a bearing for a worm *f* which meshes with a stationary worm-wheel *e* held by an angular supporting member *e'* and arranged co-axially with the planet-wheel gear.

Affixed to the band *m'* is also an arm *z* arranged at 90° with respect to the arm *d'* 40 and extending to the other side of the planet-wheel gear. The free end of this arm has attached to it a bearing *y* located oppositely to a sleeve *w* arranged upon the shaft *a'* and supporting together with said sleeve a shaft *x* to which is secured a friction wheel *i* contacting with the gear-wheel *a*, as well as with a friction disk *j* affixed to the shaft *a'*.

The carrier *m* of the planet-wheels is rotatably supported upon the shaft *b'*.

50 The worm *f* is affixed to a shaft *g'* having at its outer end a chain-wheel *g* connected by a chain *g* with another chain-wheel *g* secured to the outer end of the shaft *x*. The parts *g* *g* *g* may be replaced, of course by 55 equivalent means, such, for instance, as pul-

leys and a belt, or rope-pulleys and a rope, or the like.

The manner of operation of the gear is as follows:

Supposing, the directions of rotation of the shafts *a'* and *b'* are those indicated by the arrows II and I, the arrow I indicating the direction of the driving shaft and the arrow II indicating the direction of the driven shaft, and supposing further, that the arrow III indicates the direction of rotation of the planet-wheel carrier and the arrow IV indicates the direction of rotation of the shaft *x* with the friction wheel *i*.

At a certain distinct number of revolutions of the shaft *a'* the disk *i* is rotated in the direction of the arrow IV with a certain number of revolutions determined by its position relatively to the disk *j*. At the same time the worm *f* is rotated with the same 75 number of revolutions as that of the disk *i* and its shaft *x* by the mediation of the transmitting members *g* *g* *g*. The worm *f* which meshes with the worm-wheel *e* moves thus slowly around the latter, and as 80 it is firmly connected with the planet-wheel carrier *m* by the arm *d'* and the band *m'* the carrier *m* is turned in the direction of the arrow III. Owing to this rotation, the number of revolutions of the driven shaft *a'* 85 is reduced to a number or limit determined by the position of the disk *i*. If the number of revolutions of the driving shaft *b'* increases, also the shaft *a'* tends to rotate with an increased speed, but as then also the disk 90 *i* is rotated correspondingly quicker, the planet-wheel carrier, too, turns with a greater speed, viz. in the direction of the arrow III and by reason of the action of the disk *i* upon the transmitting members *x* *g* *g* *g* *f* *d'* *m'*, in consequence of which the 95 number of revolutions of the shaft *a'* is decreased.

It is obvious that variations in the number of revolutions of the shaft *b'* are transmitted to the shaft *a'* only in a greatly reduced measure. If, for instance, the number of revolutions of the shaft *b'* would be doubled, the first tendency of the mechanism would be to double the number of revolutions also of the shaft *a'* and of the disks *j* and *i*, as well as of the transmitting members *x* *g* *g* *g* *g* *g* and *f* and as the disk *i* rotates not only with its own shaft *x*, but also 110 around the shaft *a'*, the tendency of the ro-

tating members is to increase the number of revolutions of the disk *i*. The result is a diminution of the number of revolutions of the shaft *a'*.

5 If, however, the number of revolutions of the shaft *b'* is diminished, the effect is the reverse. Thus, even a strongly ununiformly running driving shaft *b'* will produce a nearly uniform rotation of the driven shaft 10 *a'* if a mechanism of the kind described is inserted between the two shafts. The revolutions of the driven shaft may be rendered still more uniform, to any desired degree, by arranging two or more such gears in a 15 series, as will be clear without entering into the details of such an arrangement and combination of parts.

I claim:

A planet-wheel change-speed gear, comprising, in combination; a planet-wheel gear 20 composed of two co-axial wheels, two planet-wheels located oppositely to each other between said co-axial wheels and meshing with them and of a planet-wheel carrier loosely 25 rotatable between the co-axial wheels; a sta-

tionary worm-wheel arranged at the free side of one of the said co-axial wheels; a worm meshing with said worm-wheel and being supported by the planet-wheel carrier; a shaft passing through the worm-wheel and having the adjacent co-axial wheel secured to it and supporting the planet-wheel carrier; another shaft arranged coaxially to the former and having the other co-axial wheel affixed to it; a friction disk 30 also affixed to said latter shaft at some distance from the respective co-axial wheel; another friction disk located between this wheel and the first-mentioned friction disk at right angles to both; a shaft having the other disk secured to it; a shaft having the said worm affixed to it and extending parallelly to the shaft of the last-mentioned disk; and means for transmitting rotary motion from the disk shaft to the worm 40 shaft, substantially as set forth.

In witness whereof I have hereunto set my hand.

EDMUND SCHRÖDER.
